UNITED STATES PATENT OFFICE.

WALTER G. STEWART, OF READING, PENNSYLVANIA, ASSIGNOR TO COLUMBIAN CUTLERY COMPANY, OF READING, PENNSYLVANIA, A CORPORATION OF PENNSYLVANIA.

DESIGN FOR A GRASS-HOOK.

42,310.

Specification for Design. Patented Mar. 12, 1912.

Application filed March 26, 1910. Serial No. 551,809. Term of patent 14 years.

To all whom it may concern:

Be it known that I, WALTER G. STEWART, a citizen of the United States, and a resident of the city of Reading, in the county of Berks and State of Pennsylvania, have invented a certain new, original, and ornamental Design for Grass-Hooks, of which the following is a specification, reference being had to the accompanying drawing, forming part thereof.

The figure is a plan view of a grass hook, showing my new design.

The salient features of my design consist, as shown, in shaping the blade-connecting end of the handle bar to the form of a segment of a circle corresponding in diameter with the width of the connected blade and having the chord thereof alined with the end edge of the blade; and in extending the handle-bar from said segmental end plate in a straight line with the chord thereof, to a single curvature of the bar into connecting alinement with the hand grip at its outer end.

I claim:

The ornamental design for a grass hook, as shown and described.

W. G. STEWART.

Witnesses:

D. M. STEWART,
CALEB J. BIEBER.
